[57] CLAIM

The ornamental design for an exercise machine, as shown and described.

DESCRIPTION

FIG. 1 is a front perspective view of our new design;
FIG. 2 is a rear perspective view of our new design;
FIG. 3 is a top plan view of our new design;
FIG. 4 is a right side elevation view of our new design;
FIG. 5 is a front elevation view of our new design; and,
FIG. 6 is a rear elevation view of our new design.
The left side elevation is a mirror image of the right side elevation view of FIG. 4.
The bottom of the exercise machine is planar and unornamented.
